(57) CLAIM

The ornamental design for a “base of camera,” as shown and described.

DESCRIPTION

FIG. 1 is a front perspective view of a base of camera showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an illustration of the combination of the base of the camera and a camera.

The broken lines shown in the drawings represent environmental subject matter and form no part of the claimed design.
